Primary Examiner — Cathron C Brooks*Assistant Examiner* — Samantha Q. Lawrence(74) *Attorney, Agent, or Firm* — Larson & Larson, P.A.;
Justin P. Miller; Frank Liebenow(57) **CLAIM**

We claim the ornamental design for a beam, as shown and described.

DESCRIPTION

FIG. 1 is a front elevation view of a beam showing my new design;

FIG. 2 is a back elevation view thereof;

FIG. 3 is a top plan view thereof;

FIG. 4 is a bottom plan view thereof;

FIG. 5 is a right-side elevation view thereof;

FIG. 6 is a left-side elevation view thereof; and,

FIG. 7 is a perspective view thereof.

The broken lines depicting part of a screen and additional structure in FIG. 8 are included for the purpose of illustrating environmental structure and form no part of the claimed design.

The break lines shown in FIGS. 3-7 indicate a symbolic break in length. The appearance of any portion of the article between the break lines forms no part of the claimed design.
